UNITED STATES PATENT OFFICE.

FREDERICK LOBL, OF MIDDLEBORO, MASSACHUSETTS.

DESIGN FOR A PUFF FOR APPLYING POWDER AND LIQUID PREPARATIONS.

57,685.

Specification for Design.

Patented Apr. 26, 1921.

Application filed September 29, 1920. Serial No. 413,627. Term of patent 14 years.

To all whom it may concern:

Be it known that I, FREDERICK LOBL, a subject of the Republic of Austria, and a resident of Middleboro, county of Plymouth, and Commonwealth of Massachusetts, have invented a new, original, and ornamental Design for a Puff for Applying Powder and Liquid Preparations, of which the following description, in connection with the accompanying drawings, is a specification, like characters on the drawings representing like parts.

The figure is a perspective view of one embodiment of my invention particularly adapted for the application of toilet powders.

I claim:

The ornamental design for a puff for applying powder and liquid preparations, as shown.

In testimony whereof I have signed my name to this specification,

FREDERICK LOBL.
